UNITED STATES PATENT OFFICE.

GEORGE W. BAYLIS, OF BROOKLYN, NEW YORK.

PACKING-RECEPTACLE.

No. 877,161.

Specification of Letters Patent.

Patented Jan. 21, 1908.

Application filed March 11, 1907. Serial No. 361,651.

To all whom it may concern:

Be it known that I, GEORGE W. BAYLIS, a citizen of the United States, residing at 413 Fifth street, Brooklyn, county of Kings, 5 State of New York, have invented certain new and useful Improvements in Packing-Receptacles, of which the following is a full, clear, and exact description.

My invention relates to improvements in 10 packing receptacles such as cans and the like.

The object of the invention is to provide 15 a simple and effective means whereby ready access may be had to the contents of the receptacle at any time, said means also operating to close the orifice through which the contents is delivered when a sufficient quantity has been delivered.

Figure 1 is a plan view of a receptacle fitted 20 with my improvement. Fig. 2 is a side elevation. Fig. 3 is a section on the line X-X, Fig. 1. Fig. 4 is a similar sectional view, the stopper being in a different position.

1 is the body of a can or receptacle, which 25 may be of any suitable shape or material.

2 is the bottom.

3 is the top.

3^a is a tongue-like piece formed in the top 30 of suitable outline to provide a discharge opening when said tongue 3^a is lifted. 3^b is a clip at the free end of said tongue, said free end being arranged to suitably engage the material of the receptacle adjacent thereto when the tongue is in the position shown in

35 Fig. 3. In the form shown this clip is shaped to engage the upper edge of the body 1. After the package is filled the top is suitably attached as by spinning down the edge, the tongue 3^a having first been formed by a suitable stamping or shearing process. When 40 the top is in place the contents of the receptacle is securely retained. When, however, the user desires to gain access to the interior of the can it is merely necessary to lift up the

45 tongue from the position shown in Fig. 3 to that shown in Fig. 4, whereupon a suitable amount of the contents may be poured or shaken out. When a sufficient quantity has been discharged the user has merely to press

50 down the tongue, whereupon the discharge opening is closed, as shown in Figs. 1 and 2, the clip 3^b, or an equivalent device, holding the tongue in the closed position. The tongue may be parallel sided, or, as shown in

Fig. 1, it may be swelled at the opposite 55 sides to provide a larger clearance passage for the discharge of the material, this, however, is immaterial. In cutting the tongue the incision may be made in such a manner that no material will be actually cut away, hence 60 when the tongue is pressed down into place it will effectively close the receptacle. If desired, the outer edge of the clip 3^b may be turned outwardly slightly to afford a convenient projection for engagement by the finger. 65

In the drawings the top 3 has a concaved or depressed center, which enables me to form the clip 3^b in a most convenient manner, the said clip being, when viewed in side elevation, of inverted U-shaped outline. Of 70 course the form of the clip is immaterial.

What I claim is:

1. In a receptacle, a body, a top, a tongue formed by incision in the top, the edges of 75 said tongue bearing against the adjacent edges of the top to close the receptacle said tongue extending to and engaging the side of said body.

2. In a receptacle, a body, a top, a tongue formed by incisions in the top, the edges of 80 said tongue bearing against the adjacent edges of the top to close the receptacle, and a retaining clip carried by the end of the tongue for engaging the body.

3. In a receptacle, a body, a top, a tongue 85 formed by incision in the top, the edges of said tongue bearing against the adjacent edges of the top to close the receptacle, and a retaining clip carried by the tongue, said clip being at the free end thereof. 90

4. In a receptacle, a body, a top, a tongue formed by incision in the top, the edges of 95 said tongue bearing against the adjacent edges of the top to close the receptacle, and a retaining clip carried by the tongue, said clip being at the free end thereof and being of inverted U-shaped outline when viewed from the side.

5. In a receptacle, a body, a top having a depressed portion, and crimped edges securing the body against said depressed portion, a tongue formed by two incisions in the depressed portion and extending through said crimped edges. 100

GEORGE W. BAYLIS.
